UNITED STATES PATENT OFFICE

LEON H. MARSHALL, OF SANTA CRUZ, CALIFORNIA

SWIMMING BOARD

Application filed July 27, 1929. Serial No. 381,487.

My invention relates to improvements in swimming boards, and it consists in the combinations, constructions and arrangements hereinafter described and claimed.

5 An object of my invention is to provide a swimming board which is extremely simple in construction and which may be used by beginners or experienced swimmers. The device is so designed as to support the body and yet at the same time give freedom to the arms and legs so that they can be used in their natural positions for swimming. The device may also be used as a surf board. The broad flat bottom of the device prevents it from 10 turning over easily, and the shape is designed to support the occupant in a swimming position.

Other objects and advantages will appear as the specification proceeds, and the novel 20 features of the invention will be particularly pointed out in the claims.

My invention is illustrated in the accompanying drawings forming a part of this application, in which:

25 Figure 1 is a side elevation of the device showing its use,

Figure 2 is a top plan view,

Figure 3 is an end view, and

30 Figure 4 is a section along the line 4—4 of Figure 2.

In carrying out my invention, I provide a board 1 having a rounded front 2, a curved bottom 3, and a recess or pocket 4 large enough in area to support the chest and stomach of a person. A flat portion 5 is provided between the front of the recess 4 and the front of the board 2. This portion may support the chin of the swimmer in the manner shown in Figure 1.

35 A centrally disposed bar 6 extends from the back of the board 1 and is preferably made integral therewith. This bar has an upwardly curved portion 7 that is designed to extend between the legs. A cross-bar 8 is secured to the portion 7 and extends over the backs of the legs at a point above the knees. The dotted lines 4 in Figure 3 show how the pocket 4 is rounded out so as to conform with 40 the shape of the body. The dotted line 2 represents the front 2 of the board. The bar 8 is

shown integral with the portion 7, and the under-surface of this bar is curved at 9 and 10 for engaging with the backs of the legs.

From the foregoing description of the various parts of the device, the operation thereof may be readily understood.

The device is made large enough to support a person in a swimming position in the water so that his head is above the water. As already stated, the person lies upon the board 1 so that his chest and front part of the body is received in the pocket 4. The legs straddle the bar 6 and the portion 7 and extend beneath the cross bar 8. The arms are free to move on the side of the board 1, and the legs are free to move in back of the bar 8.

The person may swim while being supported by the board, or may float around idly. The board is buoyant enough to support a person who cannot swim and yet permits the person to learn to swim.

Although I have shown and described one embodiment of my invention, it is to be understood that the same is susceptible of various changes, and I reserve the right to employ such changes as may come within the scope of the invention as claimed.

I claim:

1. A swimming board having a body portion with a substantially flat upper and lower surface and a T-shaped end extending rearwardly from the rear of the body, the rear edges of the body, the sides of the central part of the T, and the arms of the T forming recesses that will snugly receive the portions of the legs disposed above the knees.

2. A swimming board having a body portion with a substantially flat upper and lower surface and a T-shaped end extending rearwardly from the rear of the body, the rear edges of the body, the sides of the central part of the T, and the arms of the T forming recesses that will snugly receive the portions of the legs disposed above the knees, the arms of the T extending entirely across the backs of the legs and being curved on the surfaces contacting with the legs to snugly conform therewith.

LEON H. MARSHALL.
